BOBBIN DELIVERY CONTROL FOR WEFT
REPLENISHING LOOMSRichard G. Turner, Worcester, Mass., assignor to
Crompton & Knowles Loom Works, Worcester,
Mass., a corporation of Massachusetts

Application April 21, 1941, Serial No. 389,570

12 Claims. (Cl. 139—232)

This invention relates to improvements in weft replenishing looms of the type wherein several stacks of reserve bobbins form a group to supply the same kind of weft which is predominant in the fabric pattern while another stack supplies a fancy weft and it is the general object of the invention to provide means for utilizing the full capacity of the stacks in the group regardless of the ratio of fancy to predominant wefts in the fabric pattern.

When using a multi-color automatic loom to weave fabrics having a preponderance of one color with an occasional stripe, the frequently used weft is supplied by several stacks grouped in one part of the magazine while another stack is provided with a fancy weft, and provision is made for drawing the reserve bobbins from the group in rotation from the several stacks. So-called repeater mechanisms are employed to provide progressive selection of bobbins from the stacks of the group, but as heretofore constructed the selection has been effected by mechanism which operates the selector when a bobbin is transferred from the fancy stack. As a result, the prescribed order in which transfers should take place from the stacks of the group are skipped and a disproportionately large number of bobbins are drawn from the other stacks. The result of this arrangement is that some of the stacks are depleted before others and the full capacity of the group cannot be utilized.

It is an important object of my present invention to provide a control for the group which will permit operation of the selector only on such transferring operations of the loom as involve bobbins drawn from the group without operating the selector when a fancy bobbin is transferred.

As set forth more particularly hereinafter this result is accomplished by the use of a pawl which operates to advance the selector progressively according to a given sequence whenever a replenishing operation involves any stack in the group having bobbins of the same kind, together with a shield which disables the pawl and prevents progressive feeding of the selector whenever a fancy bobbin is transferred. In this way the sequence of transfers from the group is preserved even though interrupted from time to time to permit replenishment of the fancy weft.

In certain types of fabrics it is desirable to use two different kinds of fancy strands, in which case two stacks of the magazine will be assigned to two distinctive decorative wefts while the remaining stacks form the group for the bobbins of the same kind which are to be woven into the

plain part of the fabric. Certain features of my invention are equally applicable whether one or more fancy wefts were used to provide occasional stripes.

3 It is a further object of my present invention to actuate the feeding mechanism for the color control from the top shaft of the magazine which is rocked each time the magazine is set for transfer. By thus driving the controller I preserve the 10 uniform release of bobbins from the stacks in the plain group even though a transfer should be revoked by a misplaced shuttle.

With these and other objects in view which will appear as the description proceeds, my invention 15 resides in the combination and arrangement of parts hereinafter described and set forth.

In the accompanying drawings, wherein a convenient embodiment of my present invention is set forth,

20 Fig. 1 is a side elevation of a multi-color weft replenishing mechanism having applied thereto the preferred form of the invention in which two distinctive and fancy groups of bobbins are provided,

Fig. 2 is a detail front elevation looking in the direction of arrow 2, Fig. 1,

Figs. 3, 4 and 5 are views looking in the direction of arrow 3, Fig. 2, but showing the parts in different positions, and

30 Fig. 6 is a view similar to Fig. 5 but showing the modified form of the invention wherein but one fancy color is used.

In carrying my present invention into effect I prefer to employ a well-known type of multi-color weft replenishing mechanism including a magazine having several vertical stacks of reserve bobbins. Referring particularly to Fig. 1 the loom frame 10 supports a magazine R provided with four vertical stacks of reserve bobbins designated at 11, 12, 13 and 14 associated, respectively, with vertical control slides 15, 16, 17 and 18. Each slide controls a cradle designated generally at 20 which is rocked first by upward motion and then downward motion of its slide to deliver a bobbin from the corresponding stack.

The vertical motion of the slides is effected by means of a color slide 25 comprising a rod 26 slidable horizontally on the inner plate 27 of the magazine. This color slide is provided with front and back selector fingers 28 and 29, respectively, which move horizontally with the slide 25 and are so related to the vertical slides as to be able to operate but one of them at a time. When the color slide is in its extreme right position as shown in Fig. 1, finger 28 cooperates with ver-

tical slide 15 and when the color slide 25 moves rearwardly to its next station, to the left in Fig. 1, the right finger 28 cooperates with vertical slide 16. As the color slide continues to move rearwardly finger 28 cooperates first with slide 17 and then lastly with slide 18. Thus the horizontal position of the color slide 25 determines from which stack a reserve bobbin is to be drawn for transfer. The color slide is rocked by means of a rod 30 which is depressed when the weft detector not shown indicates weft exhaustion to raise whichever vertical slide is in controlling position with respect to the color slide. The rod 30 is thereafter raised to lower the previously elevated vertical slide, and it is in this 15 way that the cradles are rocked to deliver a bobbin from the selected stack.

The transerrer arm 33 is pivoted as at 34 to the magazine and has a head 35 operating in well-known manner to have a downward motion in order to move a released reserve bobbin into shuttle S in the upper shuttle box B on the lay L. When a vertical slide is depressed from its temporarily raised position a dog 37 thereon causes rocking of a top shaft 40 in such a direction as to lower a rod 41 and simultaneously raise a rod 42 connected as at 43 to an arm 44 pivoted at 45 to the magazine frame and from which depends a shuttle position detecting arm 46. When a vertical slide descends to release a bobbin preparatory to transfer the shuttle position detector 46 is moved rearwardly to a position where it will be engaged by the lay during the latter part of its advance motion and the lay thus acts to lower the rod 42 and rock shaft 40 back to normal position, raising rod 41.

That part of the mechanism thus far described is of well-known construction and of itself forms no part of my present invention and may be constructed and operated as set forth in Patents 40 Nos. 1,030,748, 1,022,108, and 1,610,562.

When a magazine of the type described is to be used for the replenishment of shuttles which weave a fabric having a preponderance of one color with an occasional fancy stripe, certain stacks are provided with bobbins of the same kind to form a plain group while another stack is provided with bobbins carrying the fancy or decorative weft. So long as the shuttle or shuttles which carry the plain weft are in action transfers take place from one or another of the stacks of the plain group, but when the fancy shuttle becomes exhausted transfer takes place from the corresponding fancy stack. As the parts are related in my present disclosure the front or right hand stacks are devoted to the plain weft while the rear stacks accommodate the fancy weft. This division of the magazine into plain and fancy groups of reserve bobbins may be similar to that contemplated in Gordon Patent No. 1,030,077 and involves a progressive sequence of motions on the part of the color slide such as will effect transfer from the plain group whenever plain weft is being replenished without requiring registry between any particular stack in the group and the active shuttle.

Referring again to Fig. 1 it will be seen that color slide rod 26 has secured thereto a collar 50 grooved as at 51 to receive a lug 52 on the upper end of a selector lever 53 pivoted on a stud 54 fixed to the magazine frame. A spring 55 holds the lug 52 and therefore the color slide 55 yielding in forward position but permits the slide 25 to be moved rearwardly either by a link 56 connected to shifting shuttle boxes not shown 70

at the opposite end of the loom, or some mechanism coordinated with them, or by other mechanism to be described. In the usual multi-color weft replenishing loom the color slide 25 will take up a different position for each active shuttle, the position being determined by the location of the drop boxes at the opposite end with respect to the lay, but in the present instance this control by the drop boxes is exercised in connection with but one or two of the stacks of bobbins, namely, stacks 13 and 14 or stack 14 alone.

The means for controlling the position of the color slide when plain weft is being woven includes a ratchet wheel 60, lock wheel 61 cooperating with a yieldable lock lever 62, and a cam which in the preferred form is designated at 63. The ratchet and lock wheels and the cam are all secured together by a bolt 64 and rotate about a fixed stud 65 secured to the magazine frame. The cam in the preferred form has three spaced high areas 66 between which are located low areas 67 and as shown herein there are six teeth on the ratchet wheel.

The selector lever 53 carries a roll 68 which cooperates with and is positioned by the cam. The latter is turned by means of a pawl 70 pivoted at 71 to an arm 72 which rocks about a stud 73 fixed with respect to the magazine frame. The lower end of rod 41 is connected as at 74 to the arm 72.

The cam 63 controls stacks 11 and 12 and upon each transferring operation the pawl 70 will be moved down on an idle stroke as the transerrer arm descends and will be raised to have a working stroke as the lay completes its forward motion. The pawl therefore has an upward or working stroke for each transfer operation and can rock cam 63 through one-sixth of a turn to cause movement of roll 68 and selector lever 53 back and forth to permit finger 28 to release bobbins first the front stack 11 and then the second stack 12 so long as the weaving of plain weft continues. Slackness in the connection between link 56 and its control at the opposite end of the loom permits a reciprocation of the color slide 25 under action of the cam 63 independently of the position of the shuttle boxes so long as plain weft is being woven.

When a decorative weft corresponding to the third stack 13 becomes active the drop boxes will have moved to a position which will cause link 56 to move the color slide rearwardly to its third position with finger 29 in control of vertical slide 11. At this time the color slide is therefore out of control of the cam, roll 68 having been moved rearwardly from the cam. When the other of the two decorative wefts is active the color slide is moved to its rearmost position and the fourth stack 14 is under control of the finger 29, and as in the previous case the cam 63 has no control over the color slide.

In the modified form of the invention set forth in Fig. 6 provision is made for drawing plain weft from stacks 11, 12 and 13 which constitute the plain group and for drawing fancy weft from but one stack. A cam 75 replaces cam 63 but the other parts remain substantially the same. Cam 75 has a long high dwell 76 corresponding to two teeth on the ratchet wheel and a long low dwell 77 also corresponding to two teeth on the ratchet wheel and in addition has two spaced intermediate short dwells 78 each corresponding to one tooth of the ratchet wheels. In this form of the invention the cam 75 draws two bobbins suc-

sively from stack 11, one bobbin from stack 12, two successively from stack 13, and one from stack 12, thus completing the sequence of six transfers. The rearmost stack 14 is the only one which can be controlled from the opposite end of the loom.

Except for the fact that in the preferred form I provide for two fancy colors, the repeater mechanism thus far described may be the same as that set forth in the previously mentioned Gordon patent. The reserve bobbins will be called from whichever stack is under control of the color slide 25 and will be transferred into the shuttle under the magazine.

The matter thus far described and also the mechanism set forth in the Gordon patent would effect rocking of the cam for each transfer so that the color slide would be moved longitudinally by a transfer which involves a fancy weft, and certain of the stacks devoted to the plain weft would be skipped with resultant disproportionately large withdrawals from certain of the plain stacks which would therefore become depleted before depletion of the stacks which are skipped. As soon as any stack becomes empty and a shuttle cannot be replenished, a stop motion not shown will stop the loom despite the fact that reserve bobbins may be in the magazine, and the remaining bobbins represent a loss of magazine capacity which requires more frequent attention on the part of the attendant who fills the magazine than would be necessary if the stacks all became exhausted at about the same time.

It may be assumed that the length of weft on all of the bobbins, both light and fancy would be of substantially the same length, so that each bobbin will run for the same number of picks before becoming exhausted. This being so, the number of replenishments of the plain weft will bear the same relation to the number of replenishments of fancy wefts as the number of plain picks in the fabric pattern bears to the fancy picks. If a fabric is being woven in which the fancy stripe occurs frequently, in the ratio for instance of one fancy pick to five plain wefts, it may be assumed that every sixth transfer will be to replenish the fancy shuttle. If under these conditions the modified form of the invention is used wherein six transfers are required for a back and forth repeat or sequence of the color slide, the fancy rear stack will be drawn upon every sixth transfer and the pawl would therefore advance the cam when the color slide is at a particular point in its sequence if prior repeater mechanisms of the Gordon type were used. This point in the sequence will occur simultaneously with replenishment of the fancy shuttle and the plain stack from which a bobbin would otherwise be derived would be skipped for all replenishments of the fancy weft. That particular plain stack would therefore provide less reserve bobbins than at the other stacks in the group and the latter would become depleted while several bobbins still remained in the skipped stack.

Not all pattern repeats will call for the ratio of five plain to one fancy pick in the fabric. Other ratios may be used from time to time and certain of them will bear such a relation to the six repeats of the sequence of motions of the color slide that the bobbins will be drawn at an uneven rate from stacks in the plain group.

In order to insure uniform rate of discharge of reserve bobbins from the stacks in the plain group I provide a shield which permits the pawl to advance the cam on those transfers only which in-

volve plain weft and will prevent the pawl from moving the cam whenever a transfer involves a fancy pick. The simpler control is that employed for the modified form of the invention shown in Fig. 6 and it will be described first. A lever 88 rockable on stud 85 has a pawl shield arm 81 the position of which is determined by a link 82 extending between the lever 88 and the selector arm 83. The lever has front and back holes 85 and 86, respectively, to receive the forward end of the link 82, but in the modified form where but one fancy weft is used the link 82 is fitted into the rear hole 86. So long as the fabric pattern calls for plain weft the color slide and control lever 83 are free to respond to the cam 75 and shield 81 will be out of engaging position relatively to pawl 70. The cam will therefore be rocked to cause the color slide to move back and forth in a sequence which requires two transfers from the front stack followed by one from the second stack after which two are drawn from the third stack and then the last of the six again drawn from the second stack. In this way each stack is required to supply the same number of bobbins for the sequence of six transfers.

Whenever the fancy weft is called roll 88 will be moved rearwardly from the part of cam 75 last in engagement with it as link 82 draws the control lever 83 to its rearmost position. Link 82 will move the shield surface 81 under pawl 70 and the latter will therefore have an idle upward or working stroke without turning the cam. When the fancy shuttle passes out of action control of the color slide 25 returns to the cam 75 and roll 88 will return to the same part of the cam which it left when the fancy shuttle became active. Thus, if the color slide were in control of the second stack 12 roll 88 would be on one of the intermediate dwells 78 and would be moved rearwardly when the fancy shuttle became active. If a replenishment of fancy weft occurred the pawl 70 would rise without turning the cam and upon resumption of plain weaving roll 88 would return to the intermediate dwell and the sequence so far as the group of plain weft is concerned would be picked up at the point where it had been interrupted. Transfer from the plain group will therefore take place in normal sequence as though no fancy weft were present and all three stacks 11, 12 and 13 will be depleted uniformly and the full capacity of the magazine can therefore be utilized.

In the preferred form link 82 enters the forward hole 85 to cause the shield to disable the pawl when either of the two fancy wefts are being woven, but permit the pawl to operate on transfer operations involving either of stacks 11 or 12. When the lever 83 moves from the full to the dotted line position in Fig. 3 under action of the cam 83 the shield will be out of controlling position with respect to the pawl. When the fancy weft corresponding to the third stack 13 becomes active the color slide will be moved by link 82 to the position indicated in Fig. 4 where the shield will have the upper part thereof under the pawl 70. When the other fancy weft corresponding to the back stack 14 becomes active the lever 83 will move to its rearmost position to elevate the shield so that the lower part of its surface 81 will hold the pawl in inactive position. Here again as already described in connection with the modified form, the cam 83 will not be moved when either of the fancy wefts are involved in a transferring opera-

tion and the roll 68 will return to the same part of the cam 63 which it left when one or the other of the fancy wefts became active, hence the sequence in which bobbins are drawn from the two stacks in the plain group will not be interrupted.

Another advantage of my invention over prior constructions grows out of the fact that the feed pawl is given its working stroke by a part which moves whenever the magazine is reset, whether a normal transfer has occurred or a revocation has been effected by a misplaced shuttle. In constructions heretofore employed it has been customary to actuate the feed pawl by the transferrer arm, and in such constructions there is no shifting of the color slide control cam if a transfer is revoked, and there is likelihood that two bobbins will be released from the same stack before the exhausted shuttle is replenished. When the magazine is set for transfer a bobbin is released by one of the cradles and so far as the number of bobbins remaining in the stack from which the bobbin is derived is concerned, it makes no difference whether the drawn bobbin is transferred or released after revocation. In prior constructions the sequence of drawing bobbins from the group of stacks assigned to plain weft would be interrupted by a revocation and bobbins would be drawn from various stacks of the group at an un-uniform rate. By driving the feed pawl from the top shaft of the magazine I am sure of an uninterrupted sequence in the order in which bobbins are drawn from the stacks when plain weft is being replenished.

From the foregoing it will be seen that I have provided simple means for permitting a transfer from a fancy stack without interrupting the normal sequence of transfers from the plain group. This result is attained by the use of a shield which prevents the pawl from having a feeding stroke with respect to the color slide cam whenever a transfer occurs from a fancy stack. It is to be understood that some pattern repeats of the fabric are helped more favorably by my invention than are other repeats, but inasmuch as the same loom will be required from time to time to weave fabrics of different pick repeats my invention gives assurance that the bobbins from the plain group of stacks will be drawn at the same rate regardless of the fabric pattern. It will also be seen that the control for the shield is derived from the lever 53 which is moved by the pattern mechanism or shuttle boxes not shown whenever a fancy transfer is to occur, and link 82 can be connected to the shield at either of two points depending upon whether one or two fancy yarns are being used. While I have set forth my invention with respect to bobbin changing looms I am not necessarily limited to looms of this type, nor am I restricted to the use of a magazine which is of the stationary type. The repeater control can be used in connection with one or more shuttles which are devoted to the weaving of the plain part of the weft and therefore will be replenished from the group of stacks which supply the plain weft. It will further be seen that the sequence in which bobbins are drawn from the stacks of the plain group is not interrupted by a revocation of transfer, due to the fact that the feed pawl receives its actuating stroke from the top shaft of the magazine rather than from the transferrer arm as heretofore.

Having thus described my invention it will be 75

seen that changes and modifications may be made therein by those skilled in the art without departing from the spirit and scope of the invention and I do not wish to be limited to the details herein disclosed, but what I claim is:

1. In a weft replenishing loom for weaving a fabric in which one type of weft is predominant and another type occurs less frequently, weft replenishing mechanism comprising a plurality of 10 stacks of reserve bobbins, certain of the stacks forming a group the bobbins of which correspond to the predominant weft and the remainder of the stacks corresponding to the less frequently occurring weft, a stack selector movable to different positions and capable of registering with any stack, depending upon the position of the selector, positioning means to move the selector progressively into registering position and in a given sequence with respect to the stacks of the 15 group when replenishing operations involving the predominant weft occur, an actuator for the positioning means, mechanism to move the selector into register with the stack of bobbins corresponding to the less frequently occurring weft, 20 and means to prevent operation of the positioning means by the actuator when the selector is in register with the last named stack corresponding to the less frequently used weft.

2. In a weft replenishing loom for weaving a 30 fabric having predominant and occasional wefts, a plurality of stacks of reserve bobbins, certain of said stacks arranged in a group and provided with reserve bobbins corresponding to the predominant weft and the remainder of the stacks 35 having reserve bobbins corresponding to the occasional weft, bobbin release mechanism for each stack, a selector movable into register with any release mechanism and capable of operating the release mechanism registering therewith, positioning means to give the selector successive motions to be in register with the several mechanisms in a given sequence when the predominant weft is being replenished, mechanism to move the selector to a position in register with release mechanism of the stack of occasional weft, an 40 actuator for said positioning means, and means to prevent operation of the positioning means by the actuator when the selector is in register with the release mechanism of the stack of occasional weft.

3. In a weft replenishing loom for weaving a 50 fabric having predominant and occasional wefts, a plurality of stacks of reserve bobbins, certain of said stacks constituting a group containing reserve bobbins corresponding to the predominant weft and the remainder of the stacks having 55 reserve bobbins corresponding to the occasional weft, bobbin release means for each stack, a selector movable to different positions to cooperate with the release means of the stacks, one at a time, a positioner for the selector movable progressively to different positions to relate the selector to the release means of the stacks in the group in a given sequence during successive 60 replenishing operations involving the predominant weft, an actuator for the positioner having a working stroke for each replenishing operation of the loom, means to cause cooperation between the actuator and the positioner to move the selector in said sequence whenever the predominant weft is replenished, and means to cause the working stroke of the actuator to be idle with respect to the positioner when the selector is 65 operatively positioned with respect to the release 70 means of the stack of occasional weft.

4. In a weft replenishing loom weaving a fabric having predominant and occasional wefts, a plurality of stacks of reserve bobbins, certain of said stacks constituting a group containing reserve bobbins corresponding to the predominant weft and the remainder of the stacks having reserve bobbins corresponding to the occasional weft, bobbin release means for each stack, a selector movable to different positions to cooperate with the release means of each stack, one at a time, a positioner for the selector movable progressively to different positions to relate the selector to the release means of the stacks in the group in a given sequence, a ratchet wheel fixed relatively to the positioner, a pawl to actuate the ratchet wheel, means to give the pawl an operative stroke relatively to the positioner whenever the predominant weft is replenished, a shield for the pawl, and means to move the shield to a position to prevent cooperation of the pawl and ratchet wheel when the selector is operatively related to the release means of the stack of occasional weft.

5. In a weft replenishing loom, a plurality of stacks of reserve bobbins, a bobbin release means for each stack, a member movable from normal to abnormal position whenever any release means operates to release a bobbin, a selector movable to different positions to register with any of the release means, one at a time, a positioner for the selector movable progressively to position the selector in register with the release means in a given sequence, means to cause the selector to operate the release means registering therewith preparatory to a replenishing operation of the loom, means to return the member from abnormal to normal position subsequent to operation of a release means, and means to connect the positioner to the member to cause the latter by a force derived therefrom to move the positioner in said sequence whenever said member has a return motion from abnormal to normal position.

6. In a weft replenishing loom wherein weft of a given type occurs predominantly in the fabric being woven and weft of another type occurs less frequently, a weft replenishing mechanism including a plurality of stacks of reserve bobbins, certain of said stacks arranged in a group and holding reserve bobbins corresponding to the predominant weft and the remainder of the stacks holding reserve bobbins corresponding to the less frequently occurring weft, means to initiate a replenishing operation with respect to any stack, a controller for the replenishing mechanism having a motion incidental to initiation of a replenishing operation, a stack selector movable to different positions and capable of registering with any stack, positioning means for the selector, operating means for the positioning means connected to and operated by said controller when the latter has said incidental motion to give the selector progressive movements to register with the stacks of the group in a given sequence when the predominant weft is being replenished, and means to prevent operation of the operating means relatively to the positioning means when the less frequently occurring weft is being replenished.

7. In a weft replenishing loom in which weft of a given type is predominant and weft of another type is less dominant in the fabric being woven, a weft replenishing mechanism including a plurality of stacks of reserve bobbins, certain of said stacks arranged in a group and holding reserve bobbins corresponding to the predominant weft

and the remainder of the stacks holding reserve bobbins corresponding to the less dominant weft, bobbin release means for each stack, means to initiate a replenishing operation with respect to any stack, a controller for the replenishing mechanism having a motion incidental to initiation of a replenishing operation, a stack selector movable into register with the release means, one at a time, and capable of effecting release of a bobbin from any stack depending upon the position of said selector, a positioner movable progressively to different positions in a given sequence to locate the selector in register with the release means of the stacks in the group according to said given sequence, an actuator for the positioner, said actuator including a pawl to be moved by said controller when the latter has said incidental motion and a ratchet wheel moving with the positioner and movable by cooperation with the pawl, a shield for the pawl, means to hold the shield in idle position relatively to the pawl when the predominant weft is being replenished to permit cooperation of the pawl and ratchet wheel, and means operated by the selector when the latter moves into register with the release means of the stack corresponding to the less dominant weft to prevent cooperation of the pawl and the ratchet wheel.

8. In a weft replenishing loom having a lay reciprocating backwardly and forwardly and provided with a shuttle box to receive a shuttle, a magazine comprising a plurality of stacks of reserve wefts, a release mechanism for each stack, a selector movable to different positions to cooperate with each of the release mechanisms one at a time, a shuttle position detector normally in non-replenishing position, means to move the shuttle position detector to replenishing position into the path of the lay whenever any release mechanism operates to release a reserve weft, the lay subsequently returning the position detector to non-replenishing position, a positioner for the selector movable to different positions to cause the selector to move into operative relation with respect to the release mechanisms in a given sequence, and an actuator for the positioner connected to the shuttle position detector and operated by the latter to move the positioner to cause movement of the selector in said sequence when the shuttle position detector is moved forwardly by the lay.

9. In a weft replenishing loom, a magazine comprising a plurality of stacks of reserve wefts, a release mechanism for each stack, a selector movable to different positions to cooperate with all of the release mechanisms one at a time, a member having a given motion subsequent to the operation of any release mechanism, a positioner for the selector movable to different positions to locate the selector operatively with respect to certain of the stacks of reserve wefts in a given sequence relatively to the stacks, a ratchet wheel moving with the positioner, a pawl to actuate the ratchet wheel, a shield for the pawl, connections between the pawl and member causing the latter to give the pawl an operating stroke with respect to the ratchet wheel whenever said member has said given motion, and means to move the shield into position to prevent the pawl from cooperating with the ratchet wheel when the selector moves to operative position with respect to other of the release mechanisms than those corresponding to said certain stacks.

10. In a weft replenishing loom weaving a fabric in which a predominant weft alternates with a

less dominant weft, a plurality of compartments holding reserve bobbins, certain of the compartments forming a group the bobbins of which correspond to the predominant weft and the remainder of the compartments corresponding to the less dominant weft, transfer mechanism to transfer a reserve bobbin drawn from any compartment, selector means to select bobbins from any compartment, a controller for the selector means to cause the selector to move progressively 10 and select bobbins in a predetermined sequence from the compartments of the group during successive replenishments of the predominant weft, additional means to move the selector to a position to select a bobbin from said remainder of the compartments, means to operate the controller whenever the transfer mechanism transfers a bobbin derived from the group, and means to prevent operation of the controller when the transfer mechanism transfers a bobbin derived from said remainder of the compartments.

11. In a weft replenishing loom weaving a fabric in which one weft is predominant and another weft is less dominant, a plurality of compartments of reserve wefts, certain of the compartments forming a group the reserve wefts of which correspond to the predominant weft and the remainder of the compartments corresponding to the less dominant weft, a reserve weft selector movable into registry with all the compartments, 30 one at a time, a positioner for the selector movable progressively to control the position of the selector and cause the latter to register successively with the compartments in the group in a given sequence, means to move the selector out

of control relatively to the positioner to register with said remainder of said compartments at any point in the sequence, means to hold the positioner in the position it occupies when the selector moves to registry with said remainder of said compartments, and means to return the selector to the control of the positioner at the same point in the sequence at which the selector previously left the control of the positioner.

12. In a weft replenishing loom weaving a fabric in which one weft is predominant and another weft is less dominant, a plurality of compartments of reserve wefts, certain of the compartments forming a group of reserve wefts of which correspond to the predominant weft and the remainder of the compartments corresponding to the less dominant weft, a selector to draw reserve wefts from all the compartments one at a time, means to control the selector including a positioner normally connected operatively to the selector, mechanism operative only at the time of replenishing operations of the loom to give the positioner progressive movements to cause the selector to draw reserve wefts from the group in 25 a given sequence with respect to the compartments in the group, and means to move the selector temporarily to abnormal position out of operative connection with said positioner and prevent operation of said mechanism to cause the selector to draw reserve wefts from said remainder of the compartments without interrupting said sequence in which said selector draws reserve wefts from the group.

RICHARD G. TURNER.
